UNITED STATES PATENT OFFICE.

EDMUND R. BARANY, OF BROOKLYN, NEW YORK, ASSIGNOR TO FRANCO ELECTRIC CORPORATION, A CORPORATION OF NEW YORK.

LENS RING.

Application filed July 26, 1922. Serial No. 577,567.

To all whom it may concern:

Be it known that I, EDMUND R. BARANY, a citizen of the United States, and resident of the borough of Brooklyn, county of 5 Kings, city and State of New York, have invented certain new and useful Improvements in Lens Rings, of which the following is a specification.

This invention relates to what are commonly known as lens rings employed in connection with flashlights as a means for obtaining the so-called lens in the position upon the flashlight head.

According to the present practice, lens rings are cast and are consequently not only heavy and cumbersome, but also expensive. The weight of such rings may be cut down materially by casting them thinner and consequently their cost may be somewhat reduced, but they are, by so doing, rendered insufficient in strength to meet the usual requirements in flashlights.

An important object of my invention is to provide a lens ring which is inexpensive 25 to manufacture extremely light and sufficiently strong to meet all necessary requirements.

Other objects and certain advantages of the invention will become apparent from the 30 following description, taken in connection with the accompanying drawings, in which—

Figure 1 is a plan view of a lens ring embodying my invention.

Figure 2 is a sectional view taken on line 35 2—2 of Figure 1.

In the drawings, wherein is shown what I at present consider the preferred form of my invention, the numeral 5 indicates an annular member which is formed with a depending flange 6, having screw-threads, rolled or otherwise provided therein, in order that the ring may be attached to the usual form of screw-threaded flashlight head.

45 In constructing the device embodying my invention, I employ sheet metal which is capable of being easily fabricated, by subjecting the same to a series of appropriate metal working operations, such as blanking, 50 forming, rolling and upsetting. By employing sheet metal it is apparent that a relatively light ring may be produced, which, when properly shaped to reinforce the same

will meet all necessary requirements when used in connection with a flashlight.

5 In forming the device embodying my invention, the annular member 5 is constructed with an inwardly turned flange 7, which is adapted to rest upon the peripheral edge of the customary lens and retain the same in 60 position upon the flashlight head when the ring is applied thereto.

In order to sufficiently reinforce the relatively thin annular member 5, I subject the same to a forming operation, employing 65 suitable dies to produce an annular channel 8 and a head or offset portion 9 intermediate the screw-threaded flange 6 and the lens retaining flange 7. The annular offset portion 9 may under certain conditions, offer sufficient reinforcement to the ring to meet all ordinary requirements, but I have found that by distorting the offset portion 9 so as to provide a plurality of spaced extensions 10, the ring is further reinforced and additional 75 rigidity is afforded.

By additional reinforcing of the ring, as above mentioned, I am enabled to produce rings having diameters as great as six inches or more, which are sufficiently strong to meet 80 all requirements in a flashlight, even though the metal employed may be relatively thin. Incidentally, by distorting the offset portion 9 to provide extensions 10, I produce a poly-sided article which is highly attractive in 85 appearance and the faces 11 of which serve to prevent the flashlight from being easily rolled when laid upon a flat surface, as, for example, a table, thus eliminating, to a great extent, the danger of having the flashlight accidentally or otherwise removed, permitting it to fall to the floor, which frequently results in the breaking of the lens or other elements embodied therein.

Having thus described my invention, I 95 claim:

A lens ring constructed from sheet metal and comprising an annular screw-threaded body formed throughout its periphery with a reinforcing offset portion, said offset portion being distorted to provide a plurality of extensions and terminating in an inwardly disposed lens retaining flange.

In testimony whereof, I have affixed my signature to this specification.

EDMUND R. BARANY.
